UNITED STATES PATENT OFFICE.

CHARLES CHALLINER, OF MANCHESTER, ENGLAND.

DESIGN FOR A METALLIC RIM FOR WHEELS.

SPECIFICATION forming part of Design No. 23,704, dated October 16, 1894.

Application filed July 20, 1894. Serial No. 518,158. Term of patent 7 years.

To all whom it may concern:

Be it known that I, CHARLES CHALLINER, a subject of the Queen of Great Britain and Ireland, residing at Manchester, in the county of Lancaster, England, have invented an Improved Design for the Metallic Rims of Wheels to be Fitted with India-Rubber or Noiseless Tires, of which the following is a specification.

My invention consists of a design for grooved metallic rims for carriage and other similar wheels, which are provided with a grooved metallic rim for the reception of an india rubber tire, and the design especially relates to rims with vertical sides and internally projecting beads.

My design is illustrated by the accompanying sheet of drawings, in which—

Figure 1 represents a side elevation of the rim, and Figs. 2 and 3 are sections through the rim, and drawn to a larger scale.

a' are the vertical sides of the rim, and a^2 are the internally projecting beads. I

make an outside bead a^3 upon the outer side a of the grooved rim, at or near the upper part of the same. (See Figs. 2 and 3.)

The design may be repeated on the inner side a' of the rim, as shown by the bead a^4 in Fig. 2.

The characteristic feature of my design is the outside bead in the outside of the rim at or near the upper part of the same.

The surface of the base inside the groove is concave, as seen at a^5 on Figs. 2 and 3, but the surface of the base outside the groove is quite flat as seen at a^6 .

I claim as my invention—

The design for a grooved wheel rim, substantially as herein shown and described.

In testimony whereof I have signed my name to this specification in the presence of two subscribing witnesses.

CHARLES CHALLINER.

Witnesses:

GEORGE DAVIES,
JNO. HUGHES.
